Primary Examiner — Ricky Pham(74) Attorney, Agent, or Firm — Millen, White, Zelano & Branigan, P.C.(57) CLAIM

The ornamental design for an index advanced grey chopping board set, as shown and described.

DESCRIPTION

FIG. 1 is a perspective view of the index advanced grey chopping board set; and,

FIG. 2 is a front view thereof.

The broken lines shown in the drawings are for illustrative purposes only and form no part of the claimed design.
